[57] CLAIM

The ornamental design for a stopper, substantially as
 shown and described.

DESCRIPTION

FIG. 1 is a side elevational view of a stopper showing
 my new design, the opposite side being a mirror image
 thereof;

FIG. 2 is a top plan view thereof;

FIG. 3 is a bottom plan view thereof; and

FIG. 4 is an enlarged detail sectional view taken along
 line 4—4 of FIG. 2.
